UNITED STATES PATENT OFFICE.

WILLIAM V. ORR, OF CLEVELAND, OHIO.

VACUUM CLEANING-MACHINE.

1,342,593.

Specification of Letters Patent.

Patented June 8, 1920.

Application filed April 19, 1917. Serial No. 163,106.

To all whom it may concern:

Be it known that I, WILLIAM V. ORR, a citizen of the United States, residing at Cleveland, in the county of Cuyahoga and 5 State of Ohio, have invented a certain new and useful Improvement in Vacuum Cleaning-Machines, of which the following is a full, clear, and exact description, reference being had to the accompanying drawings.

10 My invention relates to vacuum or suction cleaning apparatus and especially to suction cleaners having a cleaner casing and a nozzle embodied in a unitary structure and movable about the surface to be cleaned. Cleaners of this type are usually mounted on traction wheels for easy movement about the floor to different scenes of operation and generally have an operating handle pivotally attached thereto by which the cleaner may 15 be manipulated. It is sometimes desirable to have the operating handle rigidly fixed to the casing instead of pivotally connected thereto, as for instance when the cleaner is to be lifted bodily by the operating handle 20 from the floor or when the cleaner is to be lifted from one surface to another, as from step to step of a stairway or from the floor to the side walls, the ceiling or the upholstery. One object of my invention is the 25 provision of improved devices for securely locking a pivoted handle to the cleaner casing at the will of the operator, the pivoted arrangement of the handle with reference to the casing being unimpaired. Another object is the provision 30 of locking devices which do not interfere with or obstruct the removal of the handle from its pivotal points on the casing. Still another object is the provision of locking devices which are removable with 35 the operating handle and form a part thereof. Still another advantage of my invention is a locking device of this character which is simple and of few parts, is easily manipulated and inexpensive in its manufacture. 40 For a better understanding of the above noted features of my invention and other advantages which will hereinafter appear reference may be had to the accompanying drawings wherein—

45 Figure 1 is a side view of a suction cleaner embodying my invention; Fig. 2 is a plan view thereof showing certain parts broken away and certain parts in section; Fig. 3 is a perspective view of an operating fork of 50 the handle removed from the casing and carrying the locking devices and Fig. 4 is a detail view of the locking devices.

Referring to the drawings there is illustrated a suction cleaner of the self-contained type embodying a motor casing 1, a fan casing 2, a nozzle 3 and traction wheels 4. The cleaner is adapted to be moved about from one point on the floor to another in the usual manner and for manipulating the cleaner an operating handle 5 is provided, a part 55 of the operating handle being broken away for convenience in illustration. This operating handle embodies at its lower end two forks 6 (only one being shown for convenience in illustration) which are pivoted at 60 their lower ends to the motor casing 1 as illustrated. The pivotal connection comprises pins 7 anchored in seats formed on opposite sides of the motor casing, these seats having flat bearing surfaces for the reception of the lower ends of the forks having corresponding bearing surfaces. The forks are provided with apertures or sockets 8 which are adapted to receive the pivot pins 7 when the handle is attached to the motor 65 casing. The operating forks 6 are somewhat resilient and may be easily sprung into and out of engagement with the pivot pins 7 in the usual manner. The operating handle 5 is thus freely pivoted to the suction cleaner 70 casing for swinging movement in a plane parallel to the cleaner axis or parallel to the direction of movement, and is conveniently provided with a heel 9 on the lower end of the forks for engagement with the fan casing 2 whereby the downward movement of 75 the handle is arrested when it reaches a certain position.

It is sometimes desirable to fix the operating handle rigidly to the motor casing 1 80 and in accordance with my present invention I provide locking devices which co-operate with the pivotal connection 7 for bringing this about. These locking devices comprise an adjustable locking pin 10 which 85 passes through an aperture in the fork 6 removed from the aperture 8 and is adapted to engage or enter into any one of a plurality of apertures 11 provided in the motor casing 1, these apertures or recesses 90 11 being arranged on the arc of a circle whose center is at the pivotal point 7 of the operating handle. The locking pin 10 is pressed inwardly toward the motor casing by means of a leaf spring 12, this spring 110

being attached as by means of a rivet 13 to the inner side of the fork 6 and having its free end formed into a fork 14 which straddles the locking pin 10 and plays in 5 an annular groove formed therein. On the outer side of the fork and around the aperture therein is formed a cam 15 and co-operating with this cam 15 is a lug or pin 16 projecting out from one side of the locking pin 10 and by turning the locking pin in its seat in the fork in a clockwise direction the pin 16 slides up the cam surface 15 and thereby causes the withdrawal of the locking pin 10 from the apertures 11 10 in the motor casing. The tension of the leaf spring 12 is such as to press the pin toward the opening 11 and is sufficient to retain the pin 10 in any position to which it has been turned, the constant pull causing 15 the lug 16 to bear tightly against the cam 15. A depression 17 may be formed in the upper part of the cam 15 for receiving the lug 16 and more securely locking the pin 10 in the withdrawn position. The pin 10 20 is preferably provided with a knurled head 18 for convenience in turning the pin to withdraw it from the openings 11 against the tension of the leaf spring 12. The operation of the locking device is obvious from 25 the description, it being apparent that the locking pin 10 may be withdrawn at will by the operator or inserted in any of the openings 11 at the will of the operator to lock the operating handle in any desired 30 angular position with reference to the cleaner casing. It is also clear that the locking devices are contained on the operating handle itself so that upon removal of the handle from the cleaner casing the locking device including the locking pin is withdrawn from the opening 11 simultaneously 35 with the removal of the operating handle from the casing, there being no exposed locking devices remaining on the casing for 40 obstructing the removal from or the attachment to the cleaner. The simplicity of the device is obvious as well as the inexpensive nature thereof, the locking devices comprising only the leaf spring 12 and the 45 locking pin 10 with its lug 16.

While I have set forth my invention in the specific manner required by the patent statutes it is understood that the attached claims are not to be limited to the specific

devices shown except as is specifically set forth therein or is required by the prior art.

Having thus described my invention what I claim is:

1. In a suction cleaner the combination of a cleaner casing adapted to be moved about on the surface to be cleaned, an operating handle pivotally attached at its lower end to said casing, said handle having an opening therein near the pivotal point and also a shoulder adjacent the opening, and a locking pin located in said opening and having a lug adapted to coöperate with said shoulder in holding said locking pin retracted, said casing having an opening for receiving said pin for the purpose described. 70

2. In a suction cleaner the combination of a cleaner casing adapted to be moved about on the surface to be cleaned, an operating handle pivotally attached at its lower end to said casing for swinging movement in a plane parallel to the cleaner axis, said handle having an aperture therein transverse to said plane, said handle also having a cam around said opening, a locking pin adjustably located in said opening and having a lug coöperating with said cam, means for pressing said locking pin toward the cleaner casing, said casing having an opening for receiving the pin for the purpose described. 80

3. In a suction cleaner the combination of a cleaner casing adapted to be moved about on the surface to be cleaned, an operating handle pivotally attached at its lower end to said casing for swinging movement in a plane parallel to the cleaner axis, said handle having an aperture therein above the pivotal point and arranged transversely of said plane, said handle also having a cam on its outer surface and around said opening, a locking pin adjustably mounted in said opening and having a lug coöperating with said cam, said pin having an annular groove therein, and a spring attached at one end to said handle and whose free end plays in said annular groove for pressing said pin toward the cleaner casing, said casing having an opening therein for receiving said pin for the purpose described. 95

In testimony whereof I hereunto affix my 105 signature.

WILLIAM V. ORR.
